UNITED STATES PATENT OFFICE.

JOHN GRAVES, OF MILWAUKEE, WISCONSIN.

MIXING-VALVE.

1,215,928.

Specification of Letters Patent. Patented Feb. 13, 1917.

Application filed October 9, 1915. Serial No. 54,383.

To all whom it may concern:

Be it known that I, JOHN GRAVES, a citizen of the United States, residing at Milwaukee, in the county of Milwaukee and 5 State of Wisconsin, have invented new and useful Improvements in Mixing-Valves, of which the following is a specification.

This invention relates to mixing valves.

It relates more particularly to valves for 10 controlling the supply of hot and cold water to shower baths, bath tubs and the like.

Various valve mechanisms have been devised for controlling the flow of hot and cold water from separate sources to a common outlet. These mechanisms generally include a valve for each supply and either 15 separate or common operating means for the valves. Separate operating means are inconvenient and the common operating means 20 heretofore employed comprise numerous parts, occupy a large amount of space and require special plumbing connections for installation. Moreover, with the prior common operating means the valves have been 25 controlled so that when both valves are open each is only about half open.

It is important that a mixing valve be provided controlled by a single operating means which will positively control the 30 valves and operate them so that either valve may be gradually opened to its fully open position with the other held closed, and the second valve gradually opened to its fully open position with the other held fully open 35 and vice versa. It is also important in view of the fact that the supply pipes to bath tubs, basins, etc., are spaced a standard distance apart that a mixing valve be provided which may be installed without requiring alteration in standard plumbing 40 connections. This valve should be neat, compact and capable of being inexpensively manufactured and assembled. To this end the present invention has been devised.

One of the objects of the invention is to 45 provide an improved mixing valve controlled by a single operating means.

Another object is to provide an improved 50 mixing valve which may be readily applied to standard plumbing connections.

Another object is to provide a mixing 55 valve having a single operating means which will control the valves so that they may be both fully open at the same time.

Another object is to provide an improved 60 mixing valve in which the valves are posi-

tively operated by a single controlling means.

A further object is to provide a mixing 65 valve having a mechanism which will operate the valves without causing rapid deterioration thereof.

Another object is to provide a neat, compact mixing valve occupying a minimum space and applicable to standard plumbing 65 connections.

A further object is to provide a mixing valve which may be inexpensively manufactured and readily assembled.

Other objects and advantages of the invention will hereinafter appear.

The accompanying drawings illustrate an embodiment of said invention.

The views of said drawings are as follows:

Figure 1 is a perspective view of the mixing valve.

Fig. 2 is a vertical cross-section showing the valves in closed position and illustrating the operating cams in dotted lines.

Fig. 3 is a horizontal cross-section showing the valves in closed position.

Fig. 4 shows the position of the operating means with one valve fully open and the other tightly closed.

Fig. 5 shows the operating means with both valves fully open.

Fig. 6 shows the operating means with the second valve fully open and the first tightly closed.

Fig. 7 is a separated perspective view of the valve parts.

The mixing valve comprises, in general, a housing 1, having supply connections 2, valves 3 and 4 for controlling the supply connections and a cam operating means 5 mounted on a shaft 6, controlled by a handle 7 for operating the valves.

The housing 1 has a central cylindrical portion 8 and two spherical extensions 9 on each side thereof. Projecting at right angles from each of the spherical portions 8 are the supply connections 2 which are spaced so that they may be connected to standard plumbing connections without requiring alteration thereof. The supply connections are shown as provided with suitable nuts, studs and washers for connecting the same to supply pipes. The interiors of the spherical extensions communicate with the central portion of the housing through inlet ports 10 and 11 and they are arranged

to contain the valves 3 and 4 for controlling said ports. The outer ends of the spherical extensions have screw threaded openings therein into which fit suitable plugs 12 which are removable to give access to the valves.

The central portion 8 of the housing 10 in-closes the valve operating means and forms a chamber into which the inlet ports open and from which the water is discharged through a common outlet 13. The rear wall of the housing is provided with a raised portion having a socket 14 therein for receiving one end of the operating shaft 6. 15 The opposite wall of the housing has an opening therein into which fits a screw threaded plug or nut 15, forming a bearing for the operating shaft 6. A suitable cap 16 and washer 17 are arranged on the end of 20 the plug 15 for packing the operating shaft.

It should, of course, be understood that the shape of the housing may be varied to suit different requirements. The construction shown is very neat and compact, occupying a minimum amount of space and places the outlet connections in such positions that the valve may be readily applied as a standard plumbing fixture.

The valves 3 and 4 which control the inlet ports may be of any suitable type. Standard Fuller-ball valves are shown having stems 18 and 19, each provided with a slot through which passes the reduced end of the operating shaft 6. Each valve stem 35 is provided with cam surfaces which coöperate with corresponding cam surfaces controlled by the operating shaft. The valve stems are also provided with guiding projections 20 which engage the housing walls 40 along the inlet port to aid in giving the valves a straight-line motion. Straight-line motion is further insured by having the valve stems offset and by making them of such thickness that they occupy substantially the entire space between the raised portion of the rear wall of the housing and a collar 23 on the shaft 6. This construction causes the valves to move in a straight line and prevents them from being worn out rapidly by being twisted or turned on the valve seats.

The valves are operated by cams 21 and 22 carried by a squared portion of the shaft 6. Two cams are shown but it should be understood that the two cams can be made integral or that a larger number of cams can be used. The cams are fitted on the shaft in the relative position shown in Fig. 7.

The cam surfaces are peculiarly shaped to operate the valves in the desired manner. The surfaces 21^a and 22^a are substantially arcuate, having the centers of the cam openings as their centers. Consequently during the engagement of these surfaces with their respective valve stems, the corresponding

valves remain in stationary position. The other cam surfaces are also approximately arcuate but the centers of their radii do not coincide with the centers of the cam openings. Instead, the centers are located so that the cam surfaces approach each other and are rounded off on the opposite side of the cam opening from the surfaces 21^a and 22^a. It is, of course, understood that all the cam surfaces are properly rounded off and merge into one another so that the cams operate smoothly.

Each cam coöperates with two surfaces on its corresponding valve stem. These stems are slotted to allow movement thereof relative to the operating shaft 6. Each has a front and rear cam surface engaging opposite sides of the cam so that the valves are positively moved in both directions.

The operating shaft 6 which carries the cams is journaled in the socket 14 and the nut 15. It has a collar 23 between which and the raised portion of the opposite side of the housing the valve stems are loosely held. Beyond the collar 23 is a reduced section 24 which passes through the slot in the valve stem 19. This section, may, if desired, be made large enough to form a shoulder for positioning the cam 22. The shaft is squared at 25 to fit corresponding apertures 95 in the cams 21 and 22. The end of the shaft is reduced to fit the socket 14.

The valve operates in the following manner:

With the cams in the position shown in Fig. 2, the highest point on each co-acts with the outer end of its valve stem and maintains both valves tightly closed.

As the shaft is turned through the first quarter turn to move the cams to the position shown in Fig. 4, the cam 21 moves the valve 3 to open position while the cam 22 holds the valve 4 closed. This is due to the fact that the distance of the surface of cam 22 in engagement with the outer end of stem 19 from the center of the shaft remains the same while the surface of cam 21 in engagement with the outer end of the valve stem 18 from the center of the shaft becomes less and the distance of the surface of the same cam in engagement with the inner cam surface of the stem 18 from the center of the shaft becomes greater so that the valve 3 is opened and the valve 4 held closed.

During the next quarter turn of the shaft 120 the surface of cam 21 in engagement with the inner end of the valve stem 18 remains at a constant distance from the shaft center and the valve 3 is held open. However, during this movement the distance of the surface of cam 23 in engagement with the outer end of the valve stem 19 from the center of the shaft becomes less and the distance of the surface of the same cam in engagement with the inner cam surface of stem 130

19 becomes greater so that the valve 4 is gradually opened to its fully open position. Accordingly when the handle has been turned through a half turn both valves are 5 fully open.

When the shaft is turned through the third quarter of a revolution the distance of the surface of cam 21 in engagement with the inner end of valve stem 18 from the center of the shaft becomes less and the distance of the surface of said cam in engagement with the outer end of valve stem 18 from the center of the shaft becomes greater so that the valve 3 is gradually closed until at 10 the end of said quarter turn it is tightly closed. During this movement the distance of the surface of cam 22 in engagement with the inner end of stem 19 from the shaft center remains the same so that the valve 4 is 15 held open.

During the remaining quarter turn of the shaft the valve 3 is held closed for the reason that the distance of the surface of cam 21 in engagement with the outer end of stem 18 from the center of the shaft remains the same. At the same time valve 4 is gradually closed since, the distance of the surface of cam 22 in engagement with the outer end of the valve stem from the center of the shaft 25 becomes greater. When the shaft has made 80 a complete revolution both valves are again tightly closed.

It will thus be seen that an operating mechanism has been provided which will 35 positively and gradually open one valve to its fully open position during the first quarter turn and at the same time positively hold the other valve closed. The cold water, if such is controlled by the valve 3, may thus 40 be fully turned on without turning on any of the hot water. During the next quarter of a revolution of the handle the hot water valve 4 is gradually opened until when the handle has been turned through a half revolution both the hot and cold water valves 45 are fully opened and a maximum supply of mixed water may be obtained. From the half revolution position of the handle it may be turned in either direction to gradually 50 close either the hot or cold water valve and at the same time keep the other open so that the temperature of the water may be readily controlled.

In addition to the above noted desirable 55 operating features the structure is such that the valve mechanism may be made rugged and compact and inclosed in a small housing of such size that the fixture may be attached to standard plumbing connections. This is 60 highly important and desirable since the valve may be applied without requiring alterations in the plumbing and without making provisions for a large, bulky fixture.

The operating means is conveniently controlled by a single handle movable in either

direction to gradually and positively open either valve while the other is held closed, to fully open the second valve while the first is held fully open, to subsequently close either valve while the other is held open and to close the other valve.

The embodiment of the invention illustrated herein shows two inlet ports and an outlet port. If desired a larger number of inlet and outlet ports may be used, controlled 75 either by a single pair of valves each of which controls a number of ports or by a plurality of valves each controlling one or more ports.

It should be understood that the structure shown and described is for purposes of illustration only and that other structures may be devised which embody the invention and which come within the spirit and scope of the appended claims.

What I claim as new and desire to secure by Letters Patent is:—

1. A mixing valve for controlling the admission of fluid from two sources of supply to a common outlet comprising a valve for controlling the flow from each source, a single operating means to positively open one valve to full open position while the other is positively held closed, to positively open the second valve to full open position while the first is positively held fully open, to positively close either of the valves while the other is positively held fully open and to positively close the remaining valve, and a housing inclosing said elements adapted to be attached to standard plumbing connections without alteration thereof.

2. A mixing valve comprising a housing having supply connections adapted to be applied to standard plumbing connections without requiring alteration thereof, the body of said housing being located between said supply connections, a valve for each supply port in the housing and a single operating means to positively and fully open one of said valves while the other is positively held closed to positively open the second valve to full open position while the first is positively held fully open, to positively close either of the valves while the other is positively held open and to positively close the remaining valve while the other is positively held closed.

3. A mixing valve comprising a housing having two inlet ports and a common outlet, 120 a valve for each inlet port and means controlled by a single handle for positively operating said valves in both opening and closing directions to gradually open one valve to full open position while the other is held closed, to gradually open the second valve to full open position while the first is held fully open, to gradually close either of said valves while the other is held open and to gradually close the other valve.

4. A mixing valve for controlling the admission of fluid from two sources of supply to a common outlet comprising a valve for controlling the flow from each source and means carried by a single shaft to positively open one valve to full open position and positively hold the other closed, to positively open the second valve to full open position while the first is positively held fully open, to positively close either of the valves and at the same time hold the other positively fully open, and to positively close the remaining valve while the other is held positively closed, and a housing inclosing said elements adapted to be attached to standard plumbing connections without requiring alteration thereof.

5. A mixing valve comprising a housing having two inlet ports and a common outlet, a valve for each inlet and a cam mechanism controlled by a single handle for positively operating said valves in both opening and closing directions to fully open one of them while the other is held closed, to fully open the second valve while the first is held fully open, and to close either valve while the other is held fully open and to close the other valve.

6. A mixing valve adapted to be applied to standard plumbing connections without requiring alterations therein, comprising a housing having inlet ports, valves within said housing for controlling said inlet ports and a single operating means for moving said valves in both opening and closing directions, said means being controlled by a handle movable in either direction to fully open one of said valves while the other is held closed, to fully open the second valve while the first is held open and to close either valve while the first is held fully open and to close the remaining valve while the other is held closed.

7. A mixing valve for controlling the admission of fluid from two sources of supply to a common outlet comprising a valve for controlling the flow from each source, a cam carried by a single shaft and coöperating with the valve stems to move the valves in both opening and closing directions to positively open one valve to fully open position while the other is positively held closed, to positively open the second valve to fully open position while the first is positively held fully open, to positively close the first valve while the second valve is positively held fully open, and to positively close the second valve while the first is held closed and a housing inclosing said elements adapted to be attached to standard plumbing connections without alterations thereof.

8. A mixing valve having a plurality of inlet ports, a valve for each port and means operated by a single shaft to gradually and positively open one valve to full open posi-

tion while the other is positively held closed, to gradually and positively open the second valve to full open position while the first is positively held fully open, to gradually and positively close either valve while the other is positively held fully open and to gradually and positively close the remaining valve while the other is held positively closed.

9. A mixing valve comprising a housing having two inlet ports and a common outlet, a valve for each inlet port and means carried by a single shaft for positively operating said valves in both opening and closing directions so that both valves may be fully opened or tightly closed at the same time or one valve fully open and the other tightly closed.

10. A mixing valve having two inlet ports in substantial alinement, a valve for each port, said valves having stems projecting toward and overlapping each other and a cam coöperating with the stems of said valves to positively move the valves in both opening and closing directions to fully open one valve while the other is positively held closed, to fully open the second valve while the first is positively held fully open, to positively close either of the valves while the other is positively held fully open and to close the remaining valve while the other is positively held closed.

11. A mixing valve comprising a housing having two inlet ports communicating with a chamber having an outlet, a valve for each port, said valves having stems projecting into the chamber and overlapping one another, the coöperating surfaces of said stems having cam recesses therein, and cams within said recesses operated by a single shaft to move the valves in both opening and closing directions whereby a positively operating compact mixing valve is provided that can be attached to standard plumbing connections without requiring alterations therein.

12. A mixing valve comprising a housing having two inlet ports communicating with a chamber having an outlet, a valve for each port, the stems of said valves projecting into said chamber and having off-set portions which overlap each other so that a straight line motion of the valves is secured, said off-set portions having cam recesses therein and cams coöperating with said recesses to move the valves in both opening and closing directions, said cams being operated by a single shaft.

13. A mixing valve comprising a housing having inlet connections adapted to be applied to standard plumbing connections without alteration thereof, said housing having a chamber located between the inlet connections which communicates with them through inlet ports, a valve for each inlet, said valves having stems projecting into the

chamber and provided with off-set portions which overlap one another, cam recesses in said off-set portions of the valve stems and cams within said recesses carried by a single shaft for positively operating said valves in both opening and closing directions.

14. A mixing valve provided with inlet ports opening into a chamber having an outlet, a valve for each port, said valves having stems extending into the chamber and provided with off-set portions which overlap one another, cam recesses within said off-set portions, cams coöperating with said recesses carried by a single shaft journaled in the walls of the housing, said valve stems being prevented from moving laterally in one direction by coöperating surfaces on the housing and the operating shaft and being provided with guides to prevent lateral movement in the other direction so that straight line longitudinal movement of the shafts is insured and a compact positively operating structure is provided.

15. A mixing valve provided with two inlet ports and a common outlet, a valve for each inlet port, said valves having stems provided with off-set portions which overlap one another, cam recesses in said off-set portions and cams within said recesses controlled by a single shaft for positively moving the valves in both opening and closing directions so that one valve may be moved to full open position while the other is held closed, the second moved to full open position while the first is held in full open position, the first closed while the second is held in full open position, and the second closed while the first is held closed.

16. A mixing valve having a housing provided with inlet connections adapted to be

applied to standard plumbing connections without alteration thereof, a chamber between said inlet connections provided with an outlet, said chamber and inlet connections having communicating openings forming inlet ports, a valve for each port, said valves having stems projecting into the chamber which are provided with off-set portions which overlap one another so that a straight line motion of the valves is secured, cam recesses in said off-set portions of the valve stems, and cam means carried by a single shaft and adapted to coöperate with said recesses to positively move the valves in both opening and closing directions to fully open one valve while the other is held closed, to fully open the second valve while the first is held fully open, to close the first valve while the second is held fully open and to close the second valve while the first is held closed.

17. A mixing valve having a housing provided with two inlet ports communicating with a chamber having an outlet, a valve for each inlet port, said valves having stems projecting into the chamber and overlapping each other, said overlapping portions having recesses in their engaging faces, cams within said recesses adapted to engage opposite sides thereof to positively move the valves in both opening and closing directions, said cams being operated by a single shaft journaled in the housing and extending through slots in the valve stems whereby a compact positively operating structure is provided.

In witness whereof, I have hereunto subscribed my name.

JOHN GRAVES.
